Attorney, Agent, or Firm—Schroeder & Siegfried

[57] CLAIM

The ornamental design for a low-profile enclosure handle, as shown and described.

DESCRIPTION

FIG. 1 is a perspective view of a low-profile enclosure handle showing our new design;

FIG. 2 is a left side elevational view thereof;

FIG. 3 is a front elevational view thereof;

FIG. 4 is a right side elevational view thereof;

FIG. 5 is a rear elevational view thereof;

FIG. 6 is a top plan view thereof;

FIG. 7 is a bottom plan view thereof;

FIG. 8 is a side elevational view thereof, showing the handle in its unlocked position, the opposite side view being a mirror image of that shown; and,

FIG. 9 is a front elevational view thereof, showing the handle unlocked and rotated angularly.
